UNITED STATES PATENT OFFICE.

WILLIAM TRIPPE, OF HOLSTEIN, MISSOURI.

GRAIN BINDER.

Application filed October 9, 1922. Serial No. 593,247.

To all whom it may concern:

Be it known that I, WILLIAM TRIPPE, a citizen of the United States, residing at Holstein, Warren County, Missouri, have 5 invented a new and useful Grain Binder, of which the following is a specification.

This invention relates to grain binders.

An object of the invention is to provide an improved device for cooperation with the 10 needle of a grain binder to pack and compress the grain straws in a more efficient manner than is effected by the usual grain arms.

Another object of the invention is to provide 15 an improved device for cooperation with the needle of a grain binder to pack the straws of the grain closely at the time the needle operates, and to relieve a large amount of the strain from the usual retaining arm, with the result that the binding mechanism operates more easily thus requiring less power to operate the different parts 20 of the binding mechanism than in binders of usual construction.

Another object of the invention is to provide 25 an improvement of the character mentioned comprising a pivoted arm above the binder deck, and means for operating said arm as an incident to the operation of the 30 needle to compress and pack the grain straws more closely than is usual, and without the strong springs and other devices required in machines of the present construction.

Other objects will appear from the following 35 description, reference being made to the drawing in which—

Fig. 1 is a plan view showing the invention applied to the binder deck of a grain binder.

Fig. 2 is a side elevation with the shafts 40 shown in section.

The portion of the usual grain binder shown comprises an inclined binder deck 1 that may be composed of sheet metal or 45 other appropriate material and which is provided with a number of slots 2 for the operation of the packer arms 3 that are given a walking movement to pack the grain when the binder is in operation. Such walking 50 movement is imparted by rotation of the crank shaft 4 to which the packer arms are connected below the deck 1. As is well known, the grain slides downwardly on the deck 1 until caught or stopped by an arm 5 55 supported by a rock shaft 6 below the deck 1, said arm 5 being arranged to extend and

operate through a slot 7 extending upwardly from the lower end of the binder deck. The needle 8 is of usual and well known construction and is operated in a familiar manner 60 through a slot 9 that may be a continuation of the slot 7. The parts above described are of usual construction and operation and it will be understood that the needle 8 operates at the proper time after the grain straws 65 have been packed and compressed by the packer arms 3.

My present invention comprises a device pivotally supported above the binder deck 1 and, in the embodiment shown, consists of a 70 metallic bar or strap bent to provide two approximately parallel arms 10 having their upper ends equipped with hinges 11 that are secured to the deck 1 in a relationship in which the space between said arms is wide 75 enough to permit the needle 8 and the arm 5 to operate therein. The arms 10 are of sufficient length to permit the arm 5 to swing downwardly to permit the bundles to be discharged at the proper time. A spacer 12 is 80 secured between the arms 10 above the arm 5 to hold said arms 10 in proper spaced relationship. As shown, the spacer 12 is in the form of a sleeve through which a bolt 13 passes to hold the arms clamped close against 85 the ends of the spacer and to hold the spacer between the arms.

The needle 8 is provided with a pin or lug 14 extending on opposite sides thereof and arranged to engage against the lower 90 edges of the arms 10 and swing the lower ends of said arms 10 upwardly to compress and pack the grain while the needle is moving upwardly toward the knotter mechanism, not shown. Thus the arms 10 cooperate 95 directly with the needle and with the arm 5 to pack the straws of the grain during the tying or binding operation.

As is well known, the needle operates only after a sufficient amount of grain has been 100 accumulated to form a bundle. In the usual binders considerable power and strength is required for supporting the arm 5 and for operating it, since it affords the necessary resistance to the packer arms 3 and to the 105 needle. In the case of my invention, the arms 10 partly relieve the arm 5 so that less power is necessary.

While I have shown a preferred embodiment of the invention and one that has been 110 found entirely satisfactory in use, it will be understood that the construction and ar-

2
rangement may be varied within equivalent limits without departure from the nature and principle of the invention.

I do not restrict myself unessentially, but 5 what I claim and desire to secure by Letters Patent is:—

1. In a grain binder, the combination with a binder deck having a slot extending upwardly from its lower edge and another slot 10 in its upper portion in alinement with said first slot, an arm supported near the discharge edge of the deck for holding the grain on the deck and arranged to swing upwardly and downwardly through said 15 first slot, and a needle arranged to operate through said second slot, of a bifurcated member having its arms spaced apart to receive both said arm and said needle between them and permitting free movement of said 20 arm in any operative position of said member, a connection uniting said arms below said needle, hinges securing the upper ends of the arms of said member to the deck at opposite sides of said second slot above said 25 needle, and an element supported by said needle arranged to engage both of the arms of said member to raise said member as an incident to the operation of the needle in a tying operation.
2. In a grain binder, the combination with a binder deck having a slot therein and a needle arranged to operate through said slot, of a bifurcated member having its

arms spaced apart to receive said needle between them, a connection uniting said arms below said needle, hinges securing the upper ends of the arms of said member to the deck at opposite sides of said slot above said needle, and a projection on each side of said needle arranged to engage the arms of said member during the final upward movement of said needle in a tying operation.

3. In a grain binder the combination with a binder deck having a slot therein, a needle arranged to operate through said slot, and an arm supported near the lower end of the deck and arranged to swing to and from a position above the deck below said needle, of a bifurcated member having its connected ends below said arm and having its detached ends pivoted to said deck above said needle, one of said arms of said bifurcated member being at each side of said needle and said first named arm, a spacer between the arms of said bifurcated member above said first named arm and below said needle, a bolt passing through said arms of said bifurcated member and through said spacer and clamping said parts together, and an element supported by said needle arranged to engage both of the arms of said bifurcated member to raise said member as an incident to operation of the needle in a tying operation.

WILLIAM TRIPPE.
